Primary Examiner — Keli L Hill(74) *Attorney, Agent, or Firm* — Nelson Mullins Riley & Scarborough LLP(57) **CLAIM**

The ornamental design for a combination fuel canister, as shown and described.

DESCRIPTION

FIG. 1 is a perspective view of a combination fuel canister, embodying our new design;

FIG. 2 is a front view of the combination fuel canister of FIG. 1;

FIG. 3 is a rear view of the combination fuel canister of FIG. 1;

FIG. 4 is a left side view of the combination fuel canister of FIG. 1;

FIG. 5 is a right side view of the combination fuel canister of FIG. 1;

FIG. 6 is a bottom view of the combination fuel canister of FIG. 1; and,

FIG. 7 is a top view of the combination fuel canister of FIG. 1.

The broken lines of FIGS. 1-7 are illustrative of the visible environmental structure of the combination fuel canister and form no part of the claimed design.
